Specification of Letters Patent.

Patented Nov. 7, 1916.

Application filed March 31, 1916. Serial No. 87,934.

To all whom it may concern:

Be it known that I, ALEXANDER H. DREUX, a citizen of the United States, residing at Buffalo, in the county of Erie and State of New York, have invented certain new and useful Improvements in Boxes, of which the following is a full, clear, and exact description, such as will enable others skilled in the art to which it appertains to make 10 and use the same.

This invention relates to boxes, and with respect to its more specific features, to boxes made of paper or similar flexible material.

One of the objects of the invention is to 15 provide a practical box of the character referred to which is relatively inexpensive to manufacture.

Another object of the invention is the provision of a strong and symmetrical box of 20 the character referred to.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

30 In the accompanying drawings forming part of this specification and wherein similar reference characters refer to similar parts throughout the several views,—Figure 1 is a perspective view, partly in section, of 35 an embodiment of the invention; Fig. 2 is a sectional view of a portion of the box; Figs. 3, 4 and 5 are views showing successive stages of the assembling and shaping of the parts; Figs. 6 and 7 are views of a 40 slightly modified flange strip.

Referring now more specifically to the embodiment of the invention illustrated in the drawings, the numeral 1 indicates the head of a box and 2 the body portion or flange thereof, the box being of a cylindrical character, although it will be understood that it may be made of rectangular or other form without departing from the spirit of the invention. The flange of the box is 45 made of a strip which is folded longitudinally and the ends abutted or otherwise joined, as at 3, to form a continuous flange circumferentially, and the strip is also folded transversely on the line 4, which line extends circumferentially, that is, longitudi-

nally of the box. The transverse folding provides two plies 5 and 6, and one of these plies, to wit, the ply 6, which is inside the box, is shorter than the other ply, the 60 ply 6 measured transversely of the box terminating in a free end 7, which is below the free end 8 of the longer ply. The two plies 5 and 6 lie opposite each other and are preferably secured to each other by means of adhesive so as to form a uniform generally cylindrical flange strip of a relatively strong character. After the strip is folded and connected as described to provide a continuous flange, the box head 1 is introduced thereinto, one face of this head lying 65 opposite the shoulder provided by the edge 7 of the shorter ply 6. The end of the longer 70 ply is then folded to provide a shoulder opposite the other face of the head 1, the folding of this free end 8 of the longer ply 75 being preferably of a crimping character so as to provide a nicely rounded edge to this part of the box. In this wise it will be seen that the head of the box is held on the flange between the shoulder 9, which overlies 80 one face of the head, and the shoulder provided by the edge 7, which is spaced from the shoulder 9, and underlies the opposite face of the head, the two shoulders firmly retaining the head in place.

85 The plies 5 and 6 of the flange are formed from an integral flat strip of paper of suitable thickness and stiffness, such as relatively thick cardboard, and at the line 4 where the transverse fold is made this strip 90 is split part way through, so as to leave only a thin portion of the material connecting the two plies. By providing the slit the plies may be folded so as to lie flat against each other and produce a square end at the 95 folding line so that covering material 10 may be placed on the box and around the folded end of the flange and preserve a neat and smooth edge at the folded portion. By providing the plies of the flange from an integral piece of material not only will the flange be relatively stronger in construction than otherwise, but the expense of manufacture of the box may be materially lessened, and the box better preserve its symmetry. Inasmuch as a butt joint, such as referred to by the numeral 3, is of a relatively weak character under certain conditions of use, a lap joint of a construction specially adapting it for round boxes may 105 110

be employed, see Fig. 6. In this form the inner ply 6 at one end extends longitudinally beyond the end of the outer ply, as at 11, and at the other end does not extend to the 5 transverse edge of the outer ply, but stops short thereof by an amount 12 equal to the length of the tongue 11. When the transverse folded strip of Fig. 6 is folded longitudinally into cylindrical form, the tongue 10 11 overlaps the space 12, and these provide surfaces of substantial area which may be covered with adhesive and when superposed form a strong and efficient joint to hold the strip in shape. Prior to the transverse folding the strip of Fig. 6 has the shape, in 15 blank, shown in Fig. 7.

In view of the above are accomplished, among others, the objects hereinbefore referred to.

20 As many changes could be made in the above construction and many apparently widely different embodiments of this invention could be made without departing from the scope thereof, it is intended that all matter contained in the above description or 25 shown in the accompanying drawings shall be interpreted as illustrative and not in a limiting sense.

It is also to be understood that the 30 language used in the following claims is intended to cover all of the generic and specific features of the invention herein described, and all statements of the scope of the invention, which, as a matter of language, might 35 be said to fall therebetween.

Having described my invention, what I claim as new and desire to secure by Letters Patent is—

1. A box comprising a body portion composed of a strip folded both longitudinally and transversely, the plies of said strip measured transversely being of unequal 40 length and lying opposite each other, and a head having a face lying against the shoulder provided by the shorter ply, the end of 45 the longer ply opposite the longitudinal folding line of said strip being folded to provide a shoulder lying against the other face of said head.

2. A box comprising a head and a flange, 50 said flange comprising a strip folded on longitudinal lines to respectively underlie and overlie said head, and thereby support and retain said head in place.

3. A box comprising a head and a flange, 55 said flange comprising a strip slit on a longitudinal line and folded on said line to provide a ply the free longitudinal edge of which lies opposite one face of said head, the free edge of the other ply being folded to lie 60 opposite the other face of said head.

4. A box comprising a head and a flange, 65 said flange comprising a strip slit on a longitudinal line and folded on said line to provide a ply, the free longitudinal edge of which lies opposite one face of said head, the free edge of the other ply being folded to lie 70 opposite the other face of said head, said plies being adhesively secured together.

5. A body for a box comprising a strip 75 folded both longitudinally and transversely, the plies of said strip lying opposite each other, one ply providing a longitudinally disposed shoulder disposed transversely opposite and spaced from the free end of the other ply.

6. A box comprising a head and a flange, 80 said flange comprising a single strip of relatively stiff paper folded on a line longitudinally of the box so that the plies lie opposite each other, the adjacent faces of said plies being adhesively secured together.

7. A box comprising a head and a flange, 85 said flange comprising a single strip of relatively stiff paper folded on a line longitudinally of the box so that the plies lie opposite each other, the adjacent faces of said plies being adhesively secured together, the inner 90 plies at one end extending beyond the transverse edge of the outer ply and at the other end terminating inside of the adjacent transverse edge of said outer ply.

In testimony whereof I affix my signature, in the presence of two witnesses.

ALEXANDER H. DREUX.
